UNITED STATES PATENT OFFICE.

ALICE MAWBY BLAKESLEE, OF PHILADELPHIA, PENNSYLVANIA.

FABRIC STRIPPING OR CUTTING MACHINE.

1,338,551.

Specification of Letters Patent. Patented Apr. 27, 1920.

Application filed October 11, 1919. Serial No. 329,915.

To all whom it may concern:

Be it known that I, ALICE MAWBY BLAKESLEE, a citizen of the United States, residing at Philadelphia, in the county of 5 Philadelphia and State of Pennsylvania, have invented certain new and useful Improvements in Fabric Stripping or Cutting Machines, of which the following is a specification, reference being had to the accompanying drawings.

This invention relates to a fabric stripping or cutting machine, and an object of the invention is the provision of a machine of this kind which is simple, efficient and 15 practical in construction, and can be manufactured for a relatively low cost and sold at a reasonable profit.

As another object of the invention it is the aim to provide a machine consisting of 20 a suitable frame with means thereon for holding the fabric very flat and without wrinkling, and wherein means is afforded, on which the fabric may be fed to the fabric holding means, whereby the fabric may be 25 subsequently evenly stripped or cut, after which the strips may be used for various purposes.

A further object of the invention is the provision of a machine of this type particularly adapted for cutting or stripping fabric, preferably rags, though not necessarily, and including a traveling belt on which the fabric is held by super-imposed means, including cutting or stripping means beyond the holding means, whereby just as 35 the fabric or rags leave the holding means, it is evenly cut.

A still further object of the invention is the provision of an improved stripping means for the fabric or other like material 40 comprising adjacent revoluble cylindrical surfaces provided with undulated cutting parts, between which the fabric or the like passes, whereby it is cut into even strips.

As an additional object of the invention it is the aim to provide means intermediate the undulated cutting parts, to prevent the fabric or the like from slipping, and to maintain the same uniform, as it passes between the revoluble cylindrical faces of the cutting means. Furthermore as the fabric is stripped, and owing to the cutting parts being undulated, the fabric or the like is drawn taut in a transverse plane, thereby 55 insuring a cutting action, without tearing the fabric or other material.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and claimed.

In the drawings:

Figure 1 is a view in side elevation of the improved fabric cutting or stripping machine constructed in accordance with the invention.

Fig. 2 is a plan view of the same, more 75 clearly showing the cutting or severing means.

Fig. 3 is a view in side elevation, showing the opposite side of the machine.

Fig. 4 is an end view of the machine, 80 showing the guide or supporting table for the fabric removed.

Fig. 5 is a sectional view on line 5—5 of Fig. 4, and

Fig. 6 is a sectional view on line 6—6 of 85 Fig. 5.

Referring more especially to the drawings 1 designates a base, on which the feet 2 of the legs 3 of upright standards 4 rest. These standards are reinforced relatively to each 90 other by means of transversely disposed braces 5. Mounted in bearings of the upper parts of the standards are rotating shafts 6 and 7 arranged horizontally and spaced in parallelism, and keyed or feathered on the shafts as at 8 are rollers 9 and 10. These rollers 9 and 10 are substantially disk shaped, and may be constructed preferably of metal, though not necessarily for it is obvious that they may be constructed of 95 any other suitable material. If constructed of material other than metal, say for instance hard wood or the like, their cylindrical portions may be covered with metal bands (not shown) and which bands may 100 have cutting parts. However, in the present instance it has been found more practical to construct the rollers 9 and 10 of metal, and they are arranged adjacent and flat against each other and secured on the shafts 110 in any suitable manner (not shown) so as to rotate with the shafts. Certain marginal

corner edges of these rollers 9 and 10 are beveled outwardly and radially as indicated at 11, and are sharpened as shown at 12. Certain other corner edges of these rollers or disks are beveled inwardly and radially as indicated at 13. The faces of the rollers adjacent the sharpened beveled marginal corner edges have annular grooves or channels 14, which are arranged to assume positions adjacent the annular grooves or channels 15, as shown clearly in Fig. 6. It will be noted that the rollers or disks of the shaft 6 have their sharpened beveled marginal corner edges assuming positions in staggered relation to the corresponding sharpened beveled marginal edges of the rollers of the lower shaft 7, so that when the rollers of both shafts are arranged as illustrated in Fig. 6, undulated revoluble contacting surfaces are afforded, and furthermore the sharpened or cutting marginal corner edges of the super-imposed rollers will overlap and be arranged adjacent the corresponding sharpened edges of the lower rollers or disks. The fabric, preferably rags, though not necessarily, is fed between the cutting rollers, so that it may be severed into elongated strips. The rollers 9 and 10 intermediate the beveled parts of the rollers have annular grooves or channels 15, which receive rings 16 of soft material, preferably rubber or the like. When the disks or rollers 9 and 10 as shown in Figs. 5 and 6 are arranged adjacent each other, the soft or resilient rings 16 will barely frictionally contact, and their adjacent faces will act to feed the fabric between the upper and lower series of rollers, thereby not only holding the fabric flat and even, but will act as means to prevent the fabric from becoming jammed, or fed too rapidly. Furthermore owing to the undulated space between the rollers and through which the fabric passes, the fabric is stretched, and held taut, so as to facilitate the stripping or cutting action of the marginal cutting edges of the rollers. A shaft 17 is mounted in bearings 18 of the standards or uprights, and keyed or otherwise secured upon the shaft 17 is a roller 19, and this serves as a means for throwing the rags or fabric away from the machine, when they drop upon it after being cut by the cutting rollers.

55 Mounted upon one end of the shaft 7 (which carries the lower series of rollers or disks 10) is a pulley 20, which is engaged by a suitable belt 21, which in turn passes about a pulley 22 of a shaft 23. This shaft 23 is mounted in suitable bearings 24, which are disposed upon the elongated base part 25. The shaft 23 may be operated in any suitable manner and by any suitable source of power (not shown) 65 so as to furnish power to the machine.

Also mounted upon the shaft 23 is an additional pulley 26, through which any suitable power operating means (not shown) may be operatively connected. Also mounted upon the shaft 7 is a grooved pulley 27, 70 about the groove of which an endless belt 28 passes. The belt 28 in turn engages in the groove of the pulley 29, which is mounted upon one end of the shaft of the roller 19, so that power may be transmitted to 75 said roller, so that the fabric or other material being stripped may be thrown from the machine, so as to prevent the material or fabric from becoming entangled with parts of the mechanism. 80

Also mounted upon the shaft 7 at one end thereof is a gear 29, which meshes with the gear 30. The gear 30 is spaced sufficiently from one of the faces of the standards or uprights so as to provide a space for the admission of a gear 31, which is carried by the upper shaft 6. Projecting from the standards or uprights of the frame are suitable side walls 32, which are parallel to each other. Mounted in bearings of these sides are shafts 33 and 34, on which upper and lower rollers 36 and 37 are journaled to rotate with the shafts. The end rollers of one shaft are engaged by an endless belt 37^a. It will be noted that the rollers 37 are super-imposed 95 with relation to the rollers 36, and are sufficiently spaced, to permit of the endless belt traveling between the two series of rollers, so that when a piece of fabric, such as a rag or the like will be held flat and without 100 wrinkling, when passing between the rollers. By holding the fabric or rag flat and even, preventing lateral movement thereof, the fabric or rag may be more easily and quickly cut, and at the same time evenly cut, without tearing or ripping the fabric. 105

One of the end shafts of the lower series of rollers has movable therewith a spur gear 38, which meshes with the gear 31, so that when power is transmitted from the shaft 7, power in turn will be transmitted to the lower series of rollers 37. 110

A bed plate 39 is securely mounted at 40 on the sides 32, and is designed for the support of the fabric or rags to be cut. The fabric or rags to be cut is placed upon the bed plate, in a flat position, and is slid forwardly through the rollers 36 and 37, and by means of the belt or other feed 37^a the fabric or rag is caught and carried forwardly in a flat position between the belt and the rollers 36, until the fabric or rag comes in contact with the severing edges of the disk rollers 9 and 10, where it is cut in even strips. 115

The invention having been set forth, what is claimed as new and useful is:—

1. In a machine as set forth, a frame having an elongated bed, upper and lower revoluble members mounted in bearings of the 120

frame, disk rollers mounted on and movable with said member, said disk rollers having annular channels, soft resilient rings mounted in said channels, each of the upper disk 5 rollers having its annular corner portion beveled in a direction from the soft resilient ring, the opposite annular corner portion of each upper roller being beveled inwardly on a plane corresponding to the first bevel, the 10 lower disk rollers being likewise beveled but reversely to the corresponding bevels of the upper disk rollers, whereby the radial faces of the corners which are beveled from the soft resilient rings of both sets of rollers may 15 engage, thereby providing fabric severing means, the reversely arranged bevels of the upper and lower rollers forming spaces between the rollers, thereby acting to draw the fabric taut to insure severing of the 20 fabric, and feed means mounted on said lateral bed for feeding the fabric between the severing rollers.

2. In a stripping machine as set forth, a frame having a lateral bed, of upper and 25 lower revoluble severing elements having overlapping cutting edges and provided with beveled corners extending in corre-

sponding planes, thereby forming spaces between the rollers which are staggered, thereby acting to strip the fabric to insure 30 the severing of the fabric by the cutting edges, said upper and lower series of rollers having inlaid soft resilient rings acting to feed, stretch and hold taut the fabric as it passes between the rollers and feed means 35 on the lateral bed for feeding the fabric between the severing rollers.

3. In a stripping machine as set forth, a frame having a lateral bed, upper and lower revoluble severing elements having coöperatively 40 engaged cutting parts provided with staggeredly arranged spaces positioned at intervals between the rollers, said upper and lower series of rollers having coöperatively opposed, inlaid soft resilient rings alternately 45 arranged with respect to the spaces and acting to feed, stretch and hold taut the fabric as it passes between the rollers, and feeding means on the lateral bed for feeding the fabric between the severing 50 rollers.

In testimony whereof I hereunto affix my signature.

ALICE MAWBY BLAKESLEE.
